J. W. COAST, JR.,
ART OF CRACKING HYDROCARBONS.
APPLICATION FILED MAR. 22, 1917.

1,345,132.

Patented June 29, 1920.

UNITED STATES PATENT OFFICE.

JOHN W. COAST, JR., OF TULSA, OKLAHOMA, ASSIGNOR TO THE PROCESS COMPANY,
A CORPORATION OF MARYLAND.

ART OF CRACKING HYDROCARBONS.

1,345,132.

Specification of Letters Patent. Patented June 29, 1920.

Application filed March 22, 1917. Serial No. 156,652.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in the Art of Cracking Hydrocarbons, of which the following is a full, clear, and exact description, reference being had to the accompanying drawings, forming a part of this specification.

My invention relates to improvements in the art of cracking petroleum hydrocarbons, one of the objects being to protect cracking 15 stills from the injurious effects of coke-forming substances which tend to accumulate on the hottest parts of the stills. This feature of the invention increases the efficiency of the cracking apparatus by circulating the coke or carbon away from the point at which heat is transmitted to the still, thus permitting the heat to be transmitted freely from the still to the oil, at the same time avoiding the danger of overheating 20 the metal of the still, and allowing the apparatus to remain in service for a considerable period of time without removing the coke.

Another object is to increase the efficiency 30 of the apparatus by forcibly circulating the relatively cool liquid to the hottest part of the still. A further object is to increase the yield by compressing gas and forcing it into the liquid contents of the still. This gas is 35 preferably a product of distillation recovered from the condenser of a cracking apparatus.

In the preferred form of the invention all 40 of the foregoing objects are attained by conducting gas from the condenser to which the cracking still is connected, compressing such gas and forcing it into the liquid contents of the still.

Figure I is a diagrammatical view of a 5 cracking apparatus adapted for use in carrying out my method.

Fig. II is an enlarged transverse section of the still taken on the line II-II, Fig. I.

Fig. III is an enlarged fragmentary view 0 showing the discharge pipes at the lower portion of the still.

To illustrate the invention, I have shown a still 1 arranged above a heating chamber 2, and connected by means of an air cooled vapor pipe 3 to a reflux condenser 4. 5

designates a vapor pipe leading from the reflux condenser to a main condensing coil 6, from which the low boiling point product is conducted through a pipe 7 and into a receiving tank 8. The condensing coil 6 is 60 preferably arranged in a water tank 9. The air cooled vapor pipe 3 constitutes a reflux condenser, and it is inclined to allow the condensate to flow backwardly to the still.

The apparatus I have shown in particularly adapted for use in cracking high boiling point products of distillation, such, for example, as the distillates or residues resulting from the distillation of petroleum. The oil to be treated is introduced into the still 70 in any suitable manner, and any desired pressure may be obtained by regulating the valve 10, preferably located in the vapor pipe 5. The pressure in the still, vapor pipe 3 and reflux condenser 4, is preferably 75 greater than fifty pounds per square inch, and the temperature of the contents of the still preferably ranges from about 600° F. to 800° F. If the pressure regulating valve 10 is arranged in the vapor line as herein 80 shown, the contents of the still will be maintained under the desired high pressure, and the contents of the condenser 6 will be maintained under a pressure of about one atmosphere. 85

A trap, or liquid seal 11, is formed in the condensate pipe 7 to prevent the gas from passing to the receiving tank 8. This gas is 90 preferably conducted through a pipe 12 and utilized to accomplish several desirable results, as will be hereinafter pointed out.

13 designates a coke trap or catch basin, preferably in the form of a false bottom arranged in the lower portion of the still and extending from one end of the still to the other. Discharge pipes 14 and 15, arranged within the still below the false bottom 13, are provided with transverse discharge ports 16. These discharge pipes are arranged longitudinally of the still and they 100 preferably extend approximately from one end of the still to the other. The discharge ports 16 are so formed that the fluid discharged therefrom will flow from the still bottom in opposite directions. A conductor 17, leading from a compressor 18, is provided with branch pipes 14' and 15' for conducting fluid to the discharge pipes 14 and 15. Valves 19 (Fig. I) arranged in the pipes 14' and 15' may be regulated to control 110

the flow of fluid to the discharge pipes 14 and 15 at the lower portion of the still. The valves 19 may be operated alternately to circulate the liquid at the bottom of the still 5 in opposite directions. When the fluid is discharged through the pipe 14, a circulation will be created between the false bottom 13 and the hottest part of the still, thus causing the coke-forming substance to flow 10 transversely of the still and finally settle upon the false bottom 13 whereby it is held and prevented from reaching the main bottom. The direction of flow may be reversed by shutting off the supply of fluid to the pipe 15 14, and permitting the fluid to flow through the pipe 15. By circulating the liquid in this manner I prevent the coke from accumulating at the hottest part of the still, at the same time forcibly circulating the relatively cool portions of the liquid to the hot 20 still bottom.

In the preferred form of the invention, I utilize a gas for circulating the liquid contents of the still, and this gas is preferably 25 a product of distillation resulting from a cracking process. This may be conveniently accomplished by conducting gas from the condensate pipe 7, through the pipe 12, into a pump 20, and thence through a conductor

21 to the compressor 18, whereby it is compressed and forced into the lower portion of the still. By recovering the gas in this manner, compressing it, and forcing it into the liquid in the still, I increase the yield of low boiling point hydrocarbons, a large percentage of the gas being absorbed to form part of the low boiling point product. 30

I claim:—

In the art of cracking petroleum hydrocarbons, the method which comprises confining a hydrocarbon oil in a horizontal cylindrical cracking still, transmitting heat to the arcuate bottom of the still to vaporize the oil, conducting vapor from the still to a condenser, maintaining the contents of the still under pressure, compressing gas and discharging streams of the gas transversely of the arcuate bottom through which heat is transmitted to the oil, so as to force coke-forming substance across said arcuate bottom, and catching the coke-forming substance deflected from said arcuate bottom to prevent it from returning to the point at which heat is transmitted to the still. 40 45 50

In testimony that I claim the foregoing I hereunto affix my signature.

JOHN W. COAST, JR. 55
